UNITED STATES PATENT OFFICE.

GEORGE A. SEELY, OF EMMETSBURG, IOWA.

STAMP-AFFIXING MACHINE.

1,250,675.

Specification of Letters Patent. Patented Dec. 18, 1917.

Application filed August 27, 1915. Serial No. 47,657.

To all whom it may concern:

Be it known that I, GEORGE A. SEELY, a citizen of the United States, residing at Emmetsburg, in the county of Palo Alto and State of Iowa, have invented certain new and useful Improvements in Stamp-Affixing Machines, of which the following is a specification.

My invention relates to a stamp affixing machine, and is adapted to accommodate the standard stamp sheet, that is to say, a sheet of stamps divided laterally and longitudinally into rows.

It is one of the objects of my invention to provide a machine of this character which will receive the standard sheet of stamps, and may be operated to affix one stamp at a time, means being provided for severing the stamp from the sheet.

Another object resides in providing means for moistening the letter to which the stamp is to be affixed, prior to the affixing operation.

And, a still further object consists in providing means for successively advancing and alining a row of stamps in position to be severed and affixed one at a time.

With the above and other objects in view, I will now proceed to describe the preferred form of the invention which I have illustrated in the annexed drawings forming a part of this specification and in which:

Figure 1 is a side elevation of the preferred form of machine.

Fig. 2 is a top plan view of a portion of the machine shown in Fig. 1.

Fig. 3 is a sectional elevation on the line 3—3 of Fig. 2.

Fig. 4 is a sectional view on the line 4—4 of Fig. 2.

Fig. 5 is a perspective view of the guide member.

Fig. 6 is a perspective view of one of the stamp sections, showing the severing blades in position.

Fig. 7 is a top plan view of a portion of the stamp section frame, showing the end bracket in position, and

Fig. 8 is a side elevation of the bracket shown in Fig. 7.

The apparatus as shown comprises the frame 1 adapted to receive a till 2 for holding a sheet of stamps 3. At the forward side the frame 1 carries a letter support 4 and a plurality of stamp sections 5, each of which is formed with a blade 6 parallel

with, and fastened to the forward side of the frame 1 by means of screws 7. The forward edge of the frame 1 carries the rider bars 8 and 9 notched to receive the laterally extending blades 10 which divide the said rider bars into a plurality of stamp sections 5. Slidable along the said rider bars is a member 11 which contains the plunger 12 held in an upward position within the said member 11 by means of a spring 13, and is capable of being depressed when desired to affix the stamp. The said plunger member carries at its upper end a knob 14 and is equipped adjacent its lower end with a detent 15 which engages with notches 16 in the rider bar 8 so as to aline the said plungers over the different sections 5 in position to affix stamps. At each end of the rider bars is secured an adjustable bracket 16' for limiting the movement of the plunger member 11 so that the latter cannot slide out of the rider bars.

The till 2 is provided at each side with grooves 17 and in the center with apertures 18 which are spaced apart the distance of one row of stamps. Seated on the till 2 is a gage or guide member 19 which carries at each end, between the lugs 20, a block 21 provided with pins 22 which project through openings 23 in the said gage or guide member and enter the grooves 17. At the center the guide member is provided with a knob 24 beneath which is located a spring controlled pin 25 which is for engagement within the apertures 18 in moving the gage 19 to adjust the stamps. The sheet of stamps is disposed in the said till with its rear edge in engagement with the guide member 19, and its forward edge in alinement with the blades 6.

The moistener comprises a bracket 26 located at one side of the frame 1 and having swiveled therein the arm 27 controlled by the spring 28, so that the said arm is yieldably maintained in raised position. At its forward end the arm 27 carries a knob 28 and is recessed at 29 on its under side to receive a brush element 30 of substantially the width in one direction of the stamp. This brush member 30 is held in place by the wall 31 of a reservoir member 32 which is screwed or otherwise secured to the arms 27 by means of the members 33. The reservoir member 32 is apertured as shown at 34 so as to feed water to the brush 30, and by suitable use of this moisten-

ing member the letter may be dampened sufficiently to cause the stamp to adhere thereto when applied.

The operation is as follows:

5 As before stated the sheet of stamps 3, divided into rows, is placed in the till 2 with its rear edge in engagement with the gage 19. When in this position the gage is moved forward sufficiently to bring a row 10 of stamps in alinement over the stamp sections 5. The letters to be stamped are moistened by placing them under the brush 30 and depressing the lever 27 until the brush contacts with the letter. After the letters 15 have been so dampened they are placed on the letter supporting member 4 with the proper portion to affix the stamp directly beneath one of the sections 5 over which a stamp of the sheet 3 is now disposed. The 20 plunger member is then moved over the said section and depressed by a blow on the handle 14. This causes the perforations in the stamp sheet to engage with the blades 10 and 6 and sever the stamp which is carried 25 downwardly into proper affixing position by means of the plunger 12, and thus the stamp is literally sheared from the sheet and is applied to the moistened portion of the letter by the pressure exerted on the 30 handle member 14. Each time a stamp is affixed the plunger member is moved from over the empty section down the line of sections so as to use the entire row of stamps. When the row of stamps over the section 35 has been exhausted, the pin member 25 is disengaged from its member 18 and moved forwardly to the next adjacent aperture thereby disposing another row of stamps over the stamp sections when the machine 40 is again ready for use.

It is of course to be understood that the sheets of stamps 3 might be manufactured so that the different rows were of different denominations in which case the operator of 45 the machine could select the denomination of stamp required by the particular letter.

It is also to be understood that a plurality of these devices such as described 50 may be arranged in continuation so as to accommodate any number and many denominations of stamps.

It is desirable and practical to inclose the till by a glass cover, such cover having been omitted from the present drawing for the 55 sake of avoiding confusion.

While I have herein described a specific form of my invention, it is, however, to be understood that various modifications and

alterations of the arrangement and construction of parts may be resorted to in practice, without in any way departing from the spirit of the invention as defined in the appended claims.

I claim:

1. In a stamp affixing machine, the combination with affixing means, of a till for receiving a sheet of stamps and being provided in its central portion with a longitudinal series of spaced openings, the said openings being spaced apart a distance equal to the width of a stamp, a guide member arranged upon the bottom of said till and being capable of moving longitudinally therein, a detent carried by said guide and being adapted to engage in said openings, and means for yieldably holding said detent at the limit of its downward movement.

2. In a stamp affixing machine, the combination with affixing means, of a till for receiving a sheet of stamps and being provided in its central portion with a longitudinal series of spaced openings, the said openings being spaced apart a distance equal to the width of a stamp, a guide member slidably arranged within said till and extending entirely across the same, a detent carried by said guide and extending downwardly through the same and being adapted to engage within said openings, and a spring normally holding said detent at the limit of its downward movement.

3. In a stamp affixing machine, the combination with affixing means, of a till for receiving a sheet of stamps and being provided in its central portion with a longitudinal series of spaced openings, the said openings being spaced apart a distance equal to the width of a stamp, the bottom of said till adjacent the lateral edges thereof being provided with spaced longitudinally disposed grooves, a guide arranged for sliding movement within said till and extending entirely across the same, a block carried at each end of said guide and being capable of moving toward and away from said bottom, pins on said blocks extending through said guide and being adapted to engage in said grooves, and a detent carried by said guide for engagement within said openings.

In testimony whereof I affix my signature 110 in presence of two witnesses.

GEORGE A. SEELY.
